UNITED STATES PATENT OFFICE.

CHARLES E. GIBSON, OF NEW YORK, N. Y.

DESIGN FOR A DOLL.

Application filed March 11, 1922. Serial No. 1,118. Term of patent 3½ years.

To all whom it may concern:

Be it known that I, CHARLES E. GIBSON, a citizen of the United States, residing at New York, borough of Manhattan, in the county and State of New York, have invented a new, original, and ornamental Design for a Doll, of which the following is a specification, reference being had to the accompanying drawing, forming part thereof.

The figure is a perspective view of the doll.

I claim:

The ornamental design for a doll, as shown.

CHARLES E. GIBSON.
